UNITED STATES PATENT OFFICE.

ARTHUR R. OGBURN, OF NEWTON, IOWA.

MACHINE-BRAKE.

1,139,566.

Specification of Letters Patent. Patented May 18, 1915.

Application filed March 2, 1907. Serial No. 360,209.

To all whom it may concern:

Be it known that I, ARTHUR R. OGBURN, a citizen of the United States, residing at Newton, in the county of Jasper and State 5 of Iowa, have invented a certain new and useful Machine-Brake, of which the following is a specification.

The objects of my invention are to provide a governor for band cutters and feeders 10 which is designed to control the conveyer, which advances the bundles of grain into the threshing cylinder both by the quantity of straw which is being fed into the cylinder as the straw is advanced, and also by the 15 rotary speed of the driving shaft.

A further object is to provide a governor in which the controlling mechanisms regulated by the amount of straw being advanced by the conveyer, and that which is 20 controlled by the rotary speed of the driving shaft are controlled by independent mechanisms operating directly on the driven shaft.

My invention consists in certain details in 25 the construction, arrangement and combination of the various parts of the device, whereby the objects contemplated are attained, as hereinafter more fully set forth, pointed out in my claims and illustrated in 30 the accompanying drawings, in which—

Figure 1 is a side elevation of a portion of a band cutter and feeder with my governor connected with it, and with the sprocket wheel for operating the driven shaft that 35 operates the conveyer removed. Fig. 2 is a cross sectional view of one side of the band cutter and feeder, showing in elevation my governor and the mechanism by which the same is attached to the frame of the band 40 cutter and feeder. Fig. 3 is a detail view of the interior of the sprocket wheel mounted on the driven shaft which is operated from the driving shaft. Fig. 4 is a detail, cross sectional view of the band wheel and 45 sprocket wheel mounted on the driven shaft, taken on the line 4—4 of Fig. 3, designed to show their relation to each other. Fig. 5 is a detailed sectional view of the pivotal attachment of the yoke which operates the 50 band with the lever connected therewith. Fig. 6 is a perspective of the yoke which operates the band. Fig. 7 is a detail perspective view of the lever which is pivoted to the yoke and also a portion of the band at- 55 tached thereto.

Referring to the accompanying drawings,

I have used the reference numeral 10 to indicate the frame of the band cutter and feeder, the numeral 11 the ordinary conveyer upon which the bundles of grain are 60 thrown and by which they are advanced to the threshing cylinder.

I have provided the ordinary driven shaft 12 which extends across the band cutter frame 10 and by which the conveyer 11 is 65 driven. Rotatably mounted on one end of the driven shaft 12 is a sprocket 13 having a rim 14 extending inwardly from it. Secured to the driven shaft 12 and inside of the rim 14 is a collar 15 having two lugs 16 70 and 17 thereon, and also having the arms 18 and 19 formed integral with it. Pivoted to the lugs 16 and 17 are two levers, 20 and 21, to the outer end of which are pivoted respectively the shoes 22 and 23 which are de- 75 signed to engage the interior of the rim 14. Connecting the arm 18 and the lever 20 is an extensible spring 24 designed to maintain the shoe 22 in engagement with the interior of the rim 14. Connecting the arm 19 and the 80 lever 21 is a spring 25 designed to maintain the shoe 23 in engagement with the interior of the rim 14. The pin 26 which forms the pivot between the lever 20 and the shoe 22 extends a considerable distance beyond the 85 inner edge of the rim 14. The pin 27 which forms the pivot between the lever 21 and the shoe 23 also extends inwardly beyond the inner edge of the rim 14. Rotatably mounted on the driven shaft 12 inside of the 90 sprocket 13 is a band wheel 28, the outer portion of which is adjacent to the edge of the rim 14. On the band wheel 28 and adjacent to its outer periphery, I have pro- 95 vided two projections 29 and 30 to form a groove 31 between them which receives the inner end of the pin 26. On that portion of the band wheel 28 which is diametrically opposite from the projections 29 and 30, I have provided two similar projections 32 100 and 33 to form a groove 34 between them to receive inner end of the pin 27.

On account of the arrangement above described, it will be seen that when the band wheel 28 is allowed free rotation by the 105 loosening of the band 42, the sprocket wheel 13 will also rotate, and will drive the shaft 12 because the shoes 22 and 23 will be held by their springs against the rim of the sprocket wheel. When however the band 110 wheel is held against rotation, the shoes 22 and 23 will be thrown out of engagement

with the rim 14 and consequently the driven shaft will not be rotated as the sprocket 13 is driven.

Secured to the side of the frame 10 and 5 at the rear of the band wheel 28, I have provided a bracket 35 to the lower forward end of which, I have pivotally attached the lever 36, having the round head 37 thereof which is designed to enter a recess in the 10 forward end of the lever 38, which lever is pivotally attached to the rear portion of the bracket 35. In the upper portion of the bracket 35 I have provided a bearing 39 for the purpose hereinafter made clear. Pivotally connecting the forward end of the lever 36 and the rear end of the lever 38 is a coil spring 40, designed to hold these levers in the desired position relative to each other for maintaining the parts of the device in 20 their proper relation to each other. By this means I provide a pivotal connection between levers 36 and 38 so that when the free end of lever 36 is elevated the spring 40 may contract and tighten the band, hereinafter 25 described, the pivotal connection between these levers is clearly shown in Fig. 1. Pivotally attached to the forward end of the lever 36 is a screw threaded rod 41 shown in Figs. 1 and 5 of the drawings.

30 I have provided a band 42 which nearly encircles the band wheel 28 and which is pivotally secured at one end to the lever 36 and at its other end is adjustably secured to the screw threaded rod 41 by means of 35 the collar 43 and thumb screw 44. This adjustment is provided to increase or diminish the friction between the band 42 and band wheel 28 whenever this is necessary to obtain the necessary results, and to provide 40 for the wear of the band.

Pivotally attached to the forward end of the lever 36 is a yoke 45 shown clearly in Fig. 6 which has an opening 46 in its upper end designed to receive the rod 47, the lower 45 end of which is hooked at 48 so as to engage the inner portion of the end 49 of said yoke 45, when the rod 47 is sufficiently raised. This rod 47 extends through the bearing 39 on the upper end of the bracket 35 and has a pin 49 extending through it to engage the upper portion of the bearing 39, and prevent the rod from sliding downwardly when the pin 49 is in engagement with the bearing 39. Mounted on the upper 55 end of the rod 47 is a sliding member 50 which has the two arms 51 and 52 extending outwardly from its body portion through which arms the rod 47 extends. Mounted on that portion of the rod 47 which is between the arms 51 and 52 is a spring 53. Extending across the top portion of the frame 10 is a shaft 54 having a series of rods 55 extending downwardly from it in such a way that the lower ends are some distance 60 above the forward end of the conveyer 11,

as shown clearly in Figs. 1 and 2 of the drawings. Secured to the shaft 54 by means of a set screw 55^a and at right angles to said shaft, is an arm 56 which has a forked end 57, the tines of which are on opposite sides of the rod 47 and the body portion of the sliding member 50. These tines are in contact with the spring 53.

I have provided a screw threaded upper end 58 for the rod 47 on which is a thumb screw 59 for maintaining the sliding member 50 at the proper position relative to the upper end of the said rod and for raising and lowering the end of the arm 56 to adjust the position of the ends of the rods 55 above the conveyer, thus regulating the flow of straw beneath the rods.

When the straw advanced by the conveyer masses at the upper end of it and is pressed against the lower ends of the rods 55, these rods will be moved forward at their lower ends and consequently raise the free end 57 of the arm 56 which presses against the spring 53, to raise the sliding member 50 and the rod 47. As this rod is elevated sufficiently, the yoke 45 is drawn upwardly. This causes the brake band 42 to be drawn tightly around the band wheel 28 and prevents its rotation, which causes the shoes 22 and 23 to be thrown out of engagement with the rim 14, and thus throws the conveyer out of operation. It will be seen that this operation prevents the straw massing on the conveyer and clogging the cylinder to which it is advanced by the conveyer. When, however, the cylinder has disposed of the straw massed at the forward end of the conveyer, the rods 55 will drop back by gravity to their former position, and the band released from the band wheel thus allowing the shoes 22 and 23 to be thrown into engagement by the springs 24 and 25 with the interior portion of the rim 14 and thus drive the conveyer.

Pivotally attached to the sides of the frame 10 and above the band wheel 28 is a lever 60, the rear end of which enters an opening 61 in the yoke 45 formed by the two sides of the yoke and the cross pieces 62 and 63. There is an opening in the forward end of the lever 60 designed to receive the screw threaded rod 64, which rod is connected to an ordinary ball governor 65 driven by the beveled gear 66 which is supported by a bearing 67 above the ball governor. The beveled gear 66 is driven by beveled gear 68 in mesh with it which is secured to a gear 69 mounted to the sides of the frame 10 and the gear 69 in mesh with the gear 70 mounted on the driving shaft 71 through which the entire band cutter and feeder mechanism are driven.

Adjustably secured to the sides of the band cutter frame and at the rear of the gear 70 is a bearing 72 on which is rotatably 130

mounted a gear 73 in mesh with gear 70. Secured to the gear 73 is a sprocket 74. Passing over the sprocket 74 and the sprocket 13 is a sprocket chain 75, through 5 which the conveyer is driven. As the driving shaft is driven at a normal rate of speed, the ball governor will not affect in any way the operations of the conveyer, but as soon as the speed of the driving shaft diminishes 10 and is below a normal point, the balls of the ball governor will be at the interior limits of movement and the forward end of the lever 60 will be thrown downwardly and the rear end upwardly and the yoke 45 15 raised upwardly, the band tightening around the band wheel, throwing the conveyer out of operation. As the speed of the driving shaft increases again the band will be released and the conveyer driven again. It 20 will be seen that when the device above described is in practical operation, the conveyer will be driven from the driving shaft and will be thrown out of operation either by the amount of straw on the conveyer, or 25 by the governor which is controlled by the speed of the driving shaft.

Having thus described my invention, what I claim and desire to secure by Letters Patent of the United States, therefor is—

30 1. In a machine of the class described, the combination of a shaft, a friction clutch on said shaft, said friction clutch having a control band, a ball governor having an upwardly extending axis of rotation, a lever, 35 adjusting means for connecting said lever with said governor, the opposite end of said lever being operatively connected with one end of said friction clutch band to loosen the clutch and stop the shaft when the 40 speed of the governor drops below normal.

2. In a machine of the class described, the combination of a driving shaft, a friction clutch on said driving shaft and having a control band, a spring-pressed lever connected with both ends of said band and positioned to swing when the band is to be tightened or loosened, a ball governor, means for driving said governor in accordance with 45

the speed of the machine, a rock lever pivoted to swing on a horizontal axis, one 50 end of said lever being adjustably connected to said ball governor and the other end being operatively connected to tighten or loosen the band by swinging the lever to which the ends of the band are connected. 55

3. In a machine of the class described, the combination with a driving shaft, a frictional clutch carried thereby and having a control band, of a pivotally mounted lever, a lever pivotally secured to the first mentioned lever, means for connecting the last mentioned lever to the control band, means for connecting said levers, a governor, a horizontal lever connected at one end of said governor, and the opposite end of said horizontal lever being connected to the means for connecting the first mentioned levers for the purpose specified. 60 65

4. In a machine of the class described, the combination with a drive shaft, a frictional 70 clutch having a control band, of a spring actuated lever connected to the control band, a yoke pivotally connected to said lever, a centrifugal governor vertically arranged, and a horizontally arranged lever operated 75 upon at one end by said governor connecting said yoke with the governor for the purpose specified.

5. In a machine of the class described, the combination with the drive shaft, a friction 80 clutch having a control band, of a pivotally mounted lever, a second lever fulcrumed upon the first lever, a coil spring connecting said levers, the second lever being connected to both ends of the control band, a yoke connected to the second lever, a horizontally arranged lever, a centrifugal governor connected to one end of said horizontally arranged lever, and the opposite end of said horizontally arranged lever being adapted to 85 90 rest within said yoke substantially as and for the purpose specified.

ARTHUR R. OGBURN.
